TRELLIS WALL BRACKET FOR FLOWER POT

John A. Bu Gay, Chicago, Ill., assignor to Quality Molding Co., Chicago, Ill., a partnership composed of John A. Bu Gay and Stanley R. Blackwell

Application October 2, 1948, Serial No. 148,943

Term of patent 3½ years

(Cl. D35—3)

To all whom it may concern:

Be it known that I, John A. Bu Gay, a citizen of the United States of America, residing at Chicago, in the county of Cook and State of Illinois, have invented a new, original, and ornamental Design for a Trellis Wall Bracket for Flower Pot, of which the following is a specification, reference being had to the accompanying drawing, forming a part thereof.

Fig. 1 is a front elevational view of a trellis wall bracket for flower pot, showing my new design.

Fig. 2 is a side view of the same.

Fig. 3 is a top plan view of the same.

The broken lines are shown for illustrative purposes only.

I claim:

The ornamental design for a trellis wall bracket for flower pot, as shown and described.

JOHN A. BU GAY.
